UNITED STATES PATENT OFFICE,

MANFRED D. PAYNE, OF NEWARK, NEW JERSEY.

BUILDING BLOCK.

Application filed March 18, 1924. Serial No. 700,054.

To all whom it may concern:

Be it known that I, MANFRED D. PAYNE, a citizen of the United States and a resident of Newark, in the county of Essex and State 5 of New Jersey, have invented a new and Improved Building Block, of which the following is a full, clear, and exact description.

This invention relates to improvements in building blocks and has particular reference to a reinforced concrete block.

An object of the invention is to provide an improved block of simple and practical construction in which is embedded a reinforcing element so formed and arranged as 15 to impart maximum strength and durability to the block.

The above and other objects will appear more clearly from the following detailed description, when taken in connection with 20 the accompanying drawing, which illustrates a preferred embodiment of the inventive idea.

In the drawing—

Figure 1 is a perspective view of the block 25 constructed in accordance with the invention and showing the reinforcing element embedded therein; and

Figure 2 is a section substantially on the line 2—2 of Figure 1.

The body 3 of the block which is of substantially rectangular formation is made of a suitable mixture of sand and cement and provided in each end thereof with a groove 4 which combines with the groove of the 35 adjacent blocks to form an air space in a wall constructed of said blocks. The face 5 of the block is made of a mixture preferably of cement and waterproof material and is formed with portions 6 and 7 which project beyond the top and one end, respectively, of the body of the block. At the opposite end and also at the bottom of the block the face 5 terminates short of said end and bottom so that when the blocks are assembled to form a wall the portion 6 of one block will overlap the bottom edge of a superimposed block, while the portion 7 will overlap that end portion of the next adjacent block in the same horizontal plane 45 which projects beyond the end of the face 5 of the latter block. By this overlapping arrangement the blocks, when combined to form a wall, are so inter-related that a secure joint will be provided which will have 50 considerable effect in excluding moisture.

A substantially U-shaped reinforcing ele-

ment 8 in the form of a rod is embedded in the block. This rod is bent to provide a practically continuous series of angularly arranged portions 9 and 10 which combine to increase the effective width of the reinforcing element. The intermediate portion of said element is embedded in the block at a point adjacent the upper surface of the body portion thereof and extends longitudinally of the front face of the block. The portions 9 and 10 combining to form the intermediate section of the element are arranged in a plane parallel to the top and bottom of the block and the effective width 60 of said intermediate section is such that parts of the portions 9 and 10 will be projected into the rear of the face 5 and beyond the line defining the front of the body 4 of the block, so that said intermediate 65 section will not only aid in reinforcing the body but also the front face 5. The end sections of the reinforcing element are formed by bending the rod so that said sections will 70 extend from the front of the body to the back thereof and diagonally downward between opposed corners of the end of the block. In thus bending the end sections the relation of the portions 9 and 10 thereof with respect to each other is maintained so that the plane of said ends will be coincident or parallel to a plane through an end of the block extending between said opposed corners, as shown in Figure 2.

What is claimed is:

1. A reinforced building block including a body having a face, and a reinforcing element embedded in said block and having a section thereof extending longitudinally of the block adjacent the top thereof 95 and other sections extending diagonally between opposed corners of the ends of said body.

2. A reinforced building block including a body having a face, and a reinforcing element embedded in said block and having a section thereof extending longitudinally of the block adjacent the top thereof and other sections extending diagonally between opposed corners of the ends of said body, the first-named section of the reinforcing element having portions thereof embedded in the body of the block and other portions 100 embedded in the face thereof.

3. A reinforced building block including a body having a face, and a reinforcing element embedded in said block and formed of

a single length of rod bent to provide a series of angularly arranged portions and also bent to provide a plurality of sections, one of the sections being embedded in the block adjacent the upper portion of the face thereof and the other sections extending from the first-named section diagonally between opposed corners of the ends of the block, the plane of the first-named section being parallel to the top and bottom of the block, while the planes of the other sections are parallel to a plane through an end of the block extending between opposed corners thereof.

15 4. A reinforced building block including a

body, a face for said body having certain edges projecting beyond adjacent edges of said body and other edges terminating short of adjacent edges of the body, and a reinforcing element embedded in said block and having an intermediate section arranged longitudinally of the top of the block and provided with portions parts of which are embedded in the body and other parts in said face, said reinforcing element also including end sections which extend diagonally downward from said intermediate section and across the ends of said body.

MANFRED D. PAYNE.
